UNITED STATES PATENT OFFICE.

CHARLES FREDERICK GILFORD, OF CONCORD, NEW HAMPSHIRE.

AUTOMATIC ADVERTISING MACHINE.

Application filed April 11, 1928. Serial No. 269,235.

This invention aims to provide a simple means whereby a plurality of tablets may be made to move in an orbit, the tablets being exposed during a part of their travel, 5 so that they can be seen, the tablets thereby being available as an advertising medium.

It is within the province of the disclosure to improve generally and to enhance the utility of devices of that type to which the 10 invention appertains.

With the above and other objects in view which will appear as the description proceeds, the invention resides in the combination and arrangement of parts and in the 15 details of construction hereinafter described and claimed, it being understood that changes in the precise embodiment of the invention herein disclosed, may be made within the scope of what is claimed, without 20 departing from the spirit of the invention.

In the drawings:-

Figure 1 shows in front elevation, a machine constructed in accordance with the invention, parts being broken away;

25 Figure 2 is a section on the line 2—2 of Figure 1;

Figure 3 is a section on the line 3—3 of Figure 1;

Figure 4 is an end elevation;

30 Figure 5 is a section taken about on the line 5—5 of Figure 3, and illustrating one of the steps in the operation of the machine; and

Figure 6 is a fragmental elevation.

35 In carrying out the invention, there is provided a frame 1 including standards 2 in the form of plates, connected by a horizontal top plate 3, a table 4 disposed below the top plate 3, and a lower platform 5 arranged below the table 4. There are notches 6 in the corners of the top plate 3 and the lower platform 5. The table 4 is somewhat narrower than the top plate 3 and the lower platform 5. The standards 2 are supplied 40 along their longitudinal edges with trough-shaped guides 7.

Lower shafts 8, upper shafts 9, and an intermediate shaft 10 are journaled for rotation in the standards 2. The intermediate 45 shaft 10 is located above and midway between the shafts 9, and the shafts 9 are located above the shafts 8, in vertical alignment therewith, as Figure 4 of the drawings will show. One of the shafts 8 is supplied 50 with a driving means 11, of any desired kind. There are sprocket wheels 12 on the

shafts 8 and 9. The shaft 10 is supplied with guide rollers 14.

Flexible elements 15, such as sprocket chains, are mounted on the sprocket wheels 12 and on the guide wheels 14. The sprocket chains 15 have first cams 16 and second cams 17, the chains being supplied with lugs 18 located between the cams 16 and 17. The cams 16 and 17 project outwardly. The lugs 18 project inwardly. There are brackets 19 on the guides 7. On two of the brackets 19, upper stacking levers 20 are fulcrumed intermediate their ends. The stacking levers 20 are supplied at their 70 lower ends with inwardly extended arms 21 operating at a lower level than the table 4. At their upper ends, the upper stacking levers 20 have heads 22, the inner edges 23 of which are inclined. Springs 24 on the 75 brackets 19 engage the stacking levers 20 below their fulcrums, and hold the stacking levers yieldably in the vertical position shown in Figure 2.

Lower stacking levers 25 are fulcrumed 80 intermediate their ends on others of the brackets 19. The lower stacking levers 25 are equipped at their upper ends with inwardly extended arms 26 which are located at a higher level than the table 4. The 85 heads 27 are at the lower ends of the lower stacking levers 25 and have inclined edges 28. Springs 30 on the brackets hold the levers 25 vertically, as shown in Figure 2.

The heads 27 of the levers 25 are offset outwardly, as shown at 29, in Figure 1. The same construction holds with respect to the upper stacking levers 20. Owing to the fact that the levers are off-set as shown at 29, the cams 16 and 17 cooperate with the inclined 95 edges 23 of the heads 22 of the levers 20, and with the inclined edges 28 of the heads 27 of the levers 25, but do not strike the arms 21 and 26. Supports 31 in the form of upwardly extended ring strips, are 100 mounted on the guides 7 outwardly of but closely adjacent to the upper stacking levers 20. The supports 31 have inwardly extended fingers 32, and at their upper ends they have inclined surfaces 33 that slant 105 downwardly and inwardly, as seen in Figure 5. A plurality of advertising tablets 34 are mounted on the table 4 and on the lower platform 5.

Referring to Figure 2 of the drawings, 110 let it be supposed that the chains 15, under the impulse of the driving means shown at

11, in Figure 1, are moving in the direction of the arrows in Figure 2. The lugs 18 move upwardly under one of the tablets 34 that has been advanced off the platform 5 and raise that tablet until the said tablet is at a slightly higher lever than the table 4. By that time, the second cams 17 will have engaged the inclined edges 28 of the heads 27 of the lower stacking levers 25, and the 10 stacking levers 25 will be tilted on their fulcra. The arms 26 of the levers 25 are caused to move inwardly and crowd over to the left in Figure 2, the whole bunch of tablets on the table 4. When the tablets 15 34 on the table 4 are crowded over to the left, as aforesaid, one of the tablets, at the extreme left hand end of the upper row, is moved over upon the fingers 32 of the springs 30 and is there held. It will be 20 noted that when the cams 16 at the right hand side of Figure 2 move upwardly, they will tilt the lever 25 before the cam 17 tilts the lever 25, but this is of no consequence, or at least, is not detrimental.

25 As the chains 15 continue to move in the direction of the arrows in Figure 2, the cams 16 engage the edges 23 of the upper stacking levers 20 and tilt the levers, but this is not objectionable. The cams 16 continue to 30 move downwardly at the left hand side of Figure 2, and, ultimately, they ride on the inclined surfaces 33 of the resilient supports 31 and withdraw the parts 32 from beneath the left hand tablet 34 in the uppermost line of Figure 2. This permits the tablet at the extreme left hand end of the uppermost line in Figure 2 to drop downwardly on the lower platform 4, but if, for 35 any reason, the tablet happens to stick, the lugs 18 will engage the upper edge of the tablet and carry it down upon the lower platform 5. The next operation is shown in Figure 5 of the drawings, the cams 17 engaging the inclined edges 23 of the upper stacking levers 20, and tilting those levers, the arms 21 moving inwardly and shoving over the lower line of tablets on the lower platform 5, until the right hand tablet in the lower line is in position to be picked up 40 by the lugs 18. The lugs 18, the cams 17, and the cams 16, pass through the notches 6 in the corners of the top plate 3 and of the lower platform 5. The lower platform 5 extends far enough out, as shown in Figure 45 3, to hold the right hand tablet 34 in the lower row in Figure 2 against downward movement, and far enough, on the opposite side, to stop the tablet at the left hand side, from the upper row, when that tablet is carried downwardly to be operated on by the arms 21 as shown in Figure 5.

The device is simple in construction, but it affords a means whereby a plurality of tablets are caused to move vertically, and 60 horizontally, in an orbit, it being obvious

from Figure 1, that the exposed surfaces of the outermost tablets always can be seen, there being nevertheless, a shifting of the tablets at intervals, so that new advertising matter will be presented.

70

What is claimed is:—

1. In a device of the class described, a frame including a table and a platform below the table, tablets set up edgewise in a stack on the table, and in a stack on the platform, an endless flexible element movable on the frame around the table and the platform, a lug on the flexible element and so located as to carry the outermost tablet at one end of the stack on the table downwardly at one side of the frame and deposit the said tablet on the platform, and to carry the outermost tablet at one end of the stack on the platform upwardly at the opposite side of the frame to a point above the table, levers fulcrumed intermediate their ends on opposite sides of the frame, one lever being provided at its upper end with a part which slides the stack of tablets on the table in one direction, 80 to bring the said outermost tablet in the stack on the table into the path of the lug, and to move the tablet at the opposite end of the stack on the table out of the path of the lug, when said lever is tilted, the other lever being provided at its lower end with a part which slides the stack of tablets on the platform in an opposite direction to bring the said outermost tablet in the stack on the platform into the path of the lug, and to move the tablet at the opposite end of the stack on the platform out of the path of the lug, when said other lever is tilted, and means on the flexible element for engaging the lower end of the first specified lever, and the upper end of said other lever, to tilt the 90 levers as aforesaid.

2. In a device of the class described, a frame including a table and a platform below the table, tablets set up edgewise in a stack on the table, and in a stack on the platform, an endless flexible element movable on the frame around the table and the platform, a lug on the flexible element and so located as to carry the outermost tablet at one end of the stack on the table downwardly at one side of the frame and deposit the said tablet on the platform, and to carry the outermost tablet at one end of the stack on the platform upwardly at the opposite side of the frame to a point above the table, levers fulcrumed intermediate their ends on opposite sides of the frame, one lever being provided at its upper end with a part which slides the stack of tablets on the table in one direction, 110 to bring the said outermost tablet in the stack on the table into the path of the lug, and to move the tablet at the opposite end of the stack on the table out of the path of the lug, when said lever is tilted, the other lever being provided at its lower end with a part which slides the stack of tablets on the platform in an opposite direction to bring the said outermost tablet in the stack on the platform into the path of the lug, and to move the tablet at the opposite end of the stack on the platform out of the path of the lug, when said other lever is tilted, and means on the flexible element for engaging the lower end of the first specified lever, and the upper end of said other lever, to tilt the 115 levers as aforesaid.

120

125

130

which slides the stack of tablets on the platform in an opposite direction to bring the said outermost tablet in the stack on the platform into the path of the lug, and to
5 move the tablet at the opposite end of the stack on the platform out of the path of the lug, when said other lever is tilted, means on the flexible element for engaging the lower end of the first specified lever, and the upper
10 end of said other lever, to tilt the levers as aforesaid, movable means on the frame for supporting said outermost tablet in the stack on the table against downward movement, and a projection on the flexible element and engaging said movable means to release it ¹⁵ from the tablet which it supports, thereby to permit the said tablet to move downwardly.

In testimony that I claim the foregoing as my own, I have hereto affixed my signature.

CHARLES FREDERICK GILFORD.
